UNITED STATES PATENT OFFICE.

CLAY B. ATKIN, OF KNOXVILLE, TENNESSEE.

DESIGN FOR A FIREPLACE-MANTEL.

SPECIFICATION forming part of Design No. 34,151, dated February 26, 1901.

Application filed February 2, 1901. Serial No. 45,784. Term of patent 7 years.

To all whom it may concern:

Be it known that I, CLAY B. ATKIN, a citizen of the United States, residing at Knoxville, in the county of Knox and State of Tennessee, have invented and produced a new and original Design for a Fireplace-Mantel, of which the following is a specification, reference being had to the accompanying drawing, in which is represented a front elevation 10 of a mantel, showing my new design.

The base or lower portion A of the mantel is distinguished by a projecting portion or shelf *a*, having an ovolو molding and a beaded fillet around its edge, while below the same 15 is a horizontal panel *b*, having a double or duplicated ornamentation *c*, in relief, which simulates the fleur-de-lis, and also ornamented horizontal ribs *d*, arranged below and above the fleur-de-lis. The vertical side 20 panels *e* have a central ornamental rib or molding *f* extending their entire length.

The back piece or upper portion B of the mantel is characterized by a top panel *g*, having along its top edge a bead *h*, whose downwardly-curved ends *i* are enlarged, as shown, 25 and floral decorations are provided at both the center and sides of the panel. The horizontal projection or shelf *j*, below said panel *g*, is provided with a beaded fillet above an ovolو molding. Below said shelf is a panel 30 *k*, and on the sides of the same is a curved or S-shaped floral relief *l*.

What I claim is—

The design for a mantel, substantially as shown and described.

CLAY B. ATKIN.
